CLAIM

The ornamental design for a folding table top as shown and described.

DESCRIPTION

FIG. 1 is a top front perspective view of a folding table top showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof;

FIG. 7 is a bottom front perspective view thereof; and,

FIG. 8 is a bottom rear perspective view thereof.

The dashed broken lines in the figures show portions of the folding table top that form no part of the claimed design.
